[57] CLAIM

The ornamental design for a tape cassette, substantially as shown and described.

DESCRIPTION

FIG. 1 is a top plan view of a tape cassette showing our new design;

FIG. 2 is a front elevational view;

FIG. 3 is a bottom plan view; and

FIG. 4 is a rear elevational view in which the opaque tape, rollers and hub which would be seen through the transparent case have been omitted for convenience of illustration.

FIG. 1.

FIG. 2.

FIG. 3.

FIG. 4.
